ATTORNEY

UNITED STATES PATENT OFFICE.

WALTER F. KRENZ, OF MENDOTA, ILLINOIS.

CLUTCH LOCK.

Application filed November 20, 1920. Serial No. 425,469.

To all whom it may concern:

Be it known that I, WALTER F. KRENZ, a citizen of the United States, residing at Mendota, in the county of La Salle and State 5 of Illinois, have invented new and useful Improvements in Clutch Locks, of which the following is a specification.

This invention relates to improvements in motor operated vehicles and has especial relation to an attachment for a "Fordson 10 tractor," the object being to provide means whereby the clutch may be held "out" so that the tractor may remain at a standstill without shifting the gears into neutral position.

More specifically stated, the invention 15 aims to provide an attachment which may be operated to engage the foot lever which controls the clutch and hold it in depressed position, so that the engine will be disengaged from the transmission mechanism. This is especially useful when stopping the 20 tractor in a field, in that it eliminates shifting the gear into neutral, while the device is so constructed as to automatically disengage 25 when the clutch lever is slightly depressed preparatory to reengaging the clutch.

With the above and other objects in view, the invention further includes the following 30 novel features and details of construction, to be hereinafter more fully described, illustrated in the accompanying drawings and pointed out in the appended claim.

In the drawings:—

Figure 1 is an elevation of a fragmentary 35 portion of a "Fordson tractor" with the invention applied thereto.

Figure 2 is a top plan view of the same.

Figure 3 is a view similar to Figure 1 but showing the clutch pedal depressed and engaged by the pedal lock. 40

Figure 4 is a fragmentary sectional view on the line 4—4 of Figure 3.

Figure 5 is a detail perspective view of the attachment per se.

Referring specifically to the drawings, 45 wherein like characters of reference denote corresponding parts, the reference character 10 indicates a portion of the transmission housing of a Fordson tractor, to which is bolted the usual cap 11 for covering the 50 opening through which a pulley shaft is connected for the purpose of converting the

tractor into a stationary engine for the operation of various devices. The reference character 12 indicates the foot pedal which 55 controls the clutch and which is depressed for the release of the clutch and returned to engaged position under the action of a spring. All of the foregoing elements form a part of the Fordson tractor.

When it is desired to disengage the clutch, it is necessary to manually depress the foot 60 pedal 12 and hold the same in depressed position during the disengagement of the clutch and it is often desirable to hold the 65 clutch disengaged for an appreciable length of time, for example, when the operator desires to leave the seat of the machine with the engine running and without shifting the transmission into neutral, it is the purpose 70 of the present invention to provide means which is operable when the foot pedal of the clutch is depressed, to engage this pedal to hold it in depressed position. This means includes a bar 13, which has one end pivotally connected as indicated at 14, to a short link 15, which is bent intermediate of its 75 ends to form an offset portion 15', the offset portion end of this link being rigidly secured upon one of the bolts which holds the 80 plate 11 to the transmission housing, as shown at 16. Secured to the lever 13, preferably by means of the pivot bolt 14 and an additional bolt 17, is a hook arm 18, the hook being located at the outer end of this arm. 85

When it is desired to hold the clutch in disengaged position, the clutch pedal 12 is depressed by the foot of the operator and the bar 13 swung upward so that the hook 18 will engage over the clutch pedal arm, whereupon the clutch pedal will be effectively held against upward movement. When it is desired to release the clutch pedal to reengage the clutch, the said pedal may be slightly depressed so as to permit of the disengagement of the hook 18 and the bar 13 may be permitted to drop back into position or may be swung back by the operator.

The invention is susceptible of various changes in its form, proportions and minor 100 details of construction and the right is here-in reserved to make such changes as properly fall within the scope of the appended claim.

Having described the invention what is claimed is:—

The combination with a motor operated vehicle including a spring actuated clutch 5 pedal of a hand lever, a short link pivotally secured to one end thereof, an offset portion formed by said link being bent intermediate of its ends and said offset portion being

rigidly secured to the transmission housing of the vehicle, an arm secured to the pivot 10 pin of said lever and to the lever respectively and a hook formed on the free end of the arm and being adapted to engage the clutch pedal as and for the purpose specified. 15

In testimony whereof I affix my signature. 15

WALTER F. KRENZ.
